ABSTRACT OF THE DISCLOSURE

A device for the deformation of sheet metal plates is provided, wherein a mold body having a mold impression formed therein is associated with clamping means for a sheet metal plate to be deformed. In operation, the clamping means are acted upon by the shock waves of explosive deformation forces acting above the sheet metal plate and the mold impression. The higher the deformation forces are the higher will be the clamping forces with which the clamping means press the sheet metal plate against the mold body to hold the sheet metal plate in its adjusted position.

Background of the invention

This invention relates to a device for the deformation of sheet metal plates by means of explosive forces and using a granular material insulation, in a water bath or by a vacuum, during which deformation a holding down ring provides for the pressing of the edges of a sheet metal disk against the mold body edge.

Such devices are already known in the art. In one known embodiment, the holding down ring is secured by means of marginal screws to hold the sheet metal disk down but securing the sheet metal disks by means of holding down rings in connection with marginal screws does not suffice for large sheet metal disks. Already when deforming hemispheres of one meter in diameter there form folds at the outlet of the clamping ring in the last phase of the deforming process owing to a raising of the holding down ring. These folds bring additional tension to bear on the marginal screws already under maximum tension which makes unscrewing them much more difficult.

Attempts have been made to overcome this deficiency by using hydraulic clamps in the form of screw clamps. However, this practice is not realizable since the number of hydraulic clamps around the edge of the mold must be so large and the weight of the clamps so high, that the operation is too expensive. Moreover, the connecting hoses for the hydraulic clamps hinder considerably operating the device.

Summary of the invention

In order to avoid these disadvantages in the deforming of large sheet metal disks, and to be able also to deform highly rigid materials, the present invention provides a device for the deformation of sheet metal plates by means of shock waves, which comprises a mold body having a mold impression formed therein; first supporting means associated with the mold body; a holding down ring for holding a sheet metal disk in position on said mold body; a plurality of spaced apart second supporting means provided on the inner edge of the holding down ring; a plurality of clamping latches each positioned between said first supporting means associated with the mold body and said second supporting means on the holding down ring, and a vacuum conduit leading

2

through the mold body and opening into the mold impression.

The first supporting means on the mold body may consist of an inside flange, or of a pivot which, in the case of need, is mounted on a pin which is removably inserted in the mold body. The second supporting means are advantageously adjustable.

The clamping latches may be provided with a baffle plate for bringing about, by the striking shock effect, a strengthening of the clamping effect of the holding down ring through the motion of the ends of the clamping latches towards the first and second supporting means. With adjustable supporting means, the initial clamping stress of the sheet metal disk is in many cases, particularly with highly rigid sheet metal disks, not sufficient. In the device proposed by the invention the stress is increased by means of shock waves.

Brief description of the drawing

Several embodiments of the invention will now be described by way of example and with reference to the accompanying drawing, in which:

FIG. 1 is a cross sectional view of a deforming device according to the invention with inserted screw-adjustable clamping latches only one of which is shown;

FIG. 2 is a similar view showing a modification of the adjustable clamping latch of FIG. 1;

FIG. 3 is a similar view showing a modification of the mold body and another modification of the clamping latch of FIG. 1, wherein the clamping latch is pivotably connected to a pin removably inserted in the housing of the mold body;

FIG. 4 is a similar view of further modifications of FIG. 1, showing a mold body consisting of concrete and a clamping latch mounted on the mold body housing;

FIG. 5 is a similar view of a modification of FIG. 1 showing a clamping latch consisting of two articulated levers, and

FIG. 6 is a side elevational view showing a still further modification of the clamping latch of FIG. 1 that is adjustable in the socket of a baffle plate by means of a screw thread.

Description of the preferred embodiment

Referring with more particularity to the drawing in which like numerals designate like parts, the deforming device shown in FIG. 1 consists of a mold body 2 in which a mold impression 1 is formed. The mold body 2 is made of cast steel and supports a mold body housing 7 formed integral with the mold body 2. The housing 7 is open at its top. A sheet metal disk 4 to be deformed by means of a shock under granular material insulation, in a water bath or by a vacuum, is placed onto the mold body 2 so that it covers the mold impression 1. A holding down ring 5 which must be fixed during the deformation process is introduced into the mold body housing 7 from above and rests on the upper border zones of the sheet metal disk 4.

FIGS. 1, 2 and 5 show first supporting means in the form of an inwardly directed flange 8 projecting from the upper edge portion 6 of the mold body housing 7. The holding down ring 5 shown in FIG. 1 has plurality of spaced apart second supporting means in the form of upright supporting projections 11 on its inside edge. A plurality of radially extending clamping latches 9 carry each a baffle plate 10 and are positioned between the flange 8 and the upright supporting projections 11. These supporting projections 11 and the clamping latches 9 are distributed around the circumference of the mold body housing 7. The clamping latches 9 are adjusted to the

thickness of the sheet metal plate 4 to be clamped, and secured in their positions by means of screws 12 (FIG. 1) or keys 13 (FIG. 2). According to FIG. 6 the clamping latches 9a are screwable in and out of a socket 3 on the baffle plate 10 thereby making a tight clamping possible.

According to FIG. 5, the clamping latches are composed of two articulated levers 14 and 15 which support a baffle plate 10a. The upright supporting projection 11a is adjustable on the holding down ring 5 by means of screws 16. The initial position of the articulated levers 14 and 15 on the holding down ring 5 can be adjusted by the screws 16 through the intermediary of the upright supporting projection 11a. Due to the shock waves striking the baffle plates 10 the articulated levers 14 and 15 will exert a high contact pressure in the direction of their lengthening on the clamped sheet metal disk 4.

According to FIG. 3, a clamping latch 9b is mounted on a pivot 18 of a pin 20 which is removably inserted in a mold body 2.

FIG. 4 shows a mold body housing 7a in which a mold body 21 of concrete is accommodated and which supports the pivot 18 for a clamping latch 9c. The holding down ring 11c has, like the holding down ring 11b of FIG. 3, an inclined outer surface 22 for engaging the clamping latches 9b (FIG. 3) and 9c (FIG. 4), respectively.

In order to bring about the shock effect, an explosive charge 17 is located in the known manner above the sheet metal disk 4. The mold body has a vacuum conduit 19.

It is to be noted that instead of cast steel and concrete also ice may be used for the mold body.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description and all changes which come within the meaning and range of equivalency of the claims are therefore intended to be embraced therein.

What is claimed is:

1. A device for the deformation of sheet metal plates 45 by means of shock waves, comprising

(a) a mold body having a mold impression formed therein;

- (b) first supporting means associated with the mold body;
- (c) a holding down ring for holding a sheet metal disk in position on said mold body;
- (d) a plurality of spaced apart second supporting means provided on the inner edge of the holding down ring;
- (e) a plurality of clamping latches 8 each positioned between said first supporting means associated with the mold body and said second supporting means on the hold down ring, and
- (f) a vacuum conduit leading through the mold body and opening into the mold impression.

2. A device as claimed in claim 1, wherein a housing is supported by and formed integral with the mold body, said mold housing being open at its top for the introduction of the sheet metal disk to be deformed and having an inwardly directed flange at its upper edge portion which constitutes the first supporting means.

3. A device as claimed in claim 2, wherein a pivot on the mold body housing about which the clamping latch can swivel radially forms the first supporting means.

4. A device as claimed in claim 3, wherein the pivot is mounted on a pin removably inserted in an opening provided at the upper edge of the mold body.

5. A device as claimed in claim 1, where the second supporting means are variably adjustable by means of screws.

6. A device as claimed in claim 1, wherein the second supporting means are variable by means of keys.

7. A device as claimed in claim 1, wherein the second supporting means are adjustable on the holding down ring.

8. A device as claimed in claim 1, wherein the clamping latches are two articulated levers arranged to be lengthened by the shock waves.

9. A device as claimed in claim 1, whereing the clamping latches are variable in length.

10. A device as claimed in claim 1, wherein the clamping latches are provided with baffle plates.
